UNITED STATES PATENT OFFICE.

CHARLES A. LINDBERG, OF STURGIS, MICHIGAN, ASSIGNOR TO STURGIS STEEL GO-CART COMPANY, OF STURGIS, MICHIGAN.

CHILD'S CARRIAGE.

1,422,277.

Specification of Letters Patent. Patented July 11, 1922.

Application filed June 2, 1921. Serial No. 474,346.

To all whom it may concern:

Be it known that I, CHARLES A. LINDBERG, a citizen of the United States, residing at city of Sturgis, county of St. Joseph, State 5 of Michigan, have invented certain new and useful Improvements in Children's Carriages, of which the following is a specification.

This invention relates to improvements in 10 children's carriages.

The main objects of this invention are:

First, to provide an improved children's carriage in which the body may be reversed relative to the handles.

15 Second, to provide an improved reversible child's carriage in which the body is very securely supported without the use of pivot bolts or the like.

Third, to provide an improved child's 20 carriage having these advantages in which the carriage is held in its adjusted position by a yielding latch or detent which is not likely to be accidentally disengaged or released.

25 Further objects, and objects relating to structural details, will definitely appear from the detailed description to follow.

I accomplish the objects of my invention by the devices and means described in the 30 following specification. The invention is clearly defined and pointed out in the claims.

A structure which is a preferred embodiment of my invention is clearly illustrated in the accompanying drawing, forming a 35 part of this application, in which:

Fig. I is a detail plan view of parts of a child's carriage embodying the features of my invention, the body and running gear proper being omitted.

40 Fig. II is a detail side elevation of a child's carriage embodying the features of my invention.

Fig. III is a transverse section on a line corresponding to line 3-3 of Figs. I, VI 45 and VII.

Fig. IV is an enlarged detail plan view showing details of the latch or detent.

Fig. V is a detail vertical section on a line corresponding to line 5-5 of Figs. I 50 and IV.

Fig. VI is an inverted fragmentary view showing details of the body support mounting.

Fig. VII is a detail vertical section on a

line corresponding to line 7-7 of Figs. I, 55 III and VI.

Fig. VIII is a detail plan view of the blank from which one of the transverse body support members is formed.

Fig. IX is a detail perspective view of 60 one of the body support members.

In the drawing similar reference characters refer to similar parts throughout the several views, and the sectional views are taken looking in the direction of the little 65 arrows at the ends of the section lines.

Referring to the drawing, 1 represents the running gear, only portions of which are illustrated.

I provide a supporting frame carried by 70 the springs 2, the supporting frame consisting of the longitudinal or side bars 3 connected by cross bars 4. The ends 5 of the side bars project beyond the cross bars 4 and are curved for convenience in attaching 75 to the springs 2. The cross bars 4 have offsets 6 therein disposed in an opposed relation centrally between the side bars 3.

An annular track or way 7 is mounted between the side and cross bars, supports 8 80 being secured on the under side of the side bars to engage the way, the way being secured to the offsets of the cross bars 4 by the rivets 9. The way 7 is arranged so that the lower edges of the offsets project below 85 the way as shown in Figs. V and VII, the purpose of which will hereafter appear.

I provide a support for the carriage body 10, shown conventionally in Fig. II, comprising spaced transverse members 11 having 90 upwardly projecting arms 12 at the ends thereof to which the body 10 is secured. These cross members 11 are connected by the bars 13. The transverse members 11 have downward offsets 14 therein disposed 95 within the way, the shoulder or end portions having recesses 15 formed therein by striking out portions 16 from one edge. These recesses 15 receive the way so that the body support is rotatably retained upon the way. 100

The bearing points of the body support are substantially spaced so that a very secure foundation is provided. One of the transverse members is provided with a latch or detent 17 which is pivoted at 18 on one of 105 the offsets and provided with a recess 19 adapted to coact with the offsets of the cross members 4. This latch or detent has a

spring 20 yieldingly holding it in engaging position. An arm 21 on the latch overlies the cross member, thereby coacting with the pivot in supporting the detent. This detent 5 is adapted to be automatically disengaged on considerable pressure being applied to swing the body, but is sufficient to prevent accidental swinging of the body.

My improved reversible carriage is very 10 strong and durable and at the same time is comparatively economical to manufacture.

I have illustrated only such parts of a carriage as seem necessary for proper disclosure of my improvements, as the structural details thereof, other than the reversible support features, form no part of my present invention.

Having thus described my invention, what 20 I claim as new and desire to secure by Letters Patent, is:

1. In a carriage, the combination of a supporting frame, comprising side members and spaced cross bars provided with opposed centrally disposed inwardly projecting offsets, 25 an annular way mounted between said side members and cross members with the lower edges of the offsets of the cross members projecting below the lower edge of the way, a body support, comprising transverse members and connecting members therefor, said transverse members having central downward offsets therein disposed within said way, the shoulder portions of said offsets having recesses therein receiving said way, 30 a latch pivoted on one of said transverse body support members to coact with the projecting lower edges of the offsets of said supporting frame cross members, and a spring for said latch.

40 2. In a carriage, the combination of a supporting frame, comprising side members and spaced cross bars, an annular way mounted between said side members and cross members, a body support, comprising 45 transverse members and connecting members therefor, said transverse members having central downward offsets therein disposed within said way, the shoulder portions of said offsets having recesses therein receiving said way.

50 3. In a carriage, the combination of a supporting frame, comprising side members and spaced cross bars provided with opposed centrally disposed inwardly projecting offsets, an annular way mounted between said side members and cross members with the lower edges of the offsets of the cross members projecting below the lower edge of the way, a body support, comprising 55 transverse members and connecting members therefor, said transverse members having central downward offsets therein disposed

within said way in bearing engagement therewith, a latch pivoted on one of said transverse body support members to coact 65 with the projecting lower edges of the offsets of said supporting frame cross members, and a spring for said latch.

4. In a carriage, the combination of a supporting frame, comprising side members 70 and spaced cross bars, an annular way mounted between said side members and cross members, a body support, comprising transverse members and connecting members therefor, said transverse members having 75 central downward offsets therein disposed within said way in bearing engagement therewith.

5. In a carriage, the combination of a supporting frame, comprising side members 80 and spaced cross bars provided with opposed centrally disposed inwardly projecting offsets, an annular way mounted on said frame with the lower edges of the offsets of the cross members projecting below the lower 85 edge of the way, a body support, comprising transverse members and connecting members therefor, said transverse members having offsets therein engaging said way, a latch pivoted on one of said transverse body support 90 members to coact with the projecting lower edges of the offsets of said supporting frame cross members, and a spring for said latch.

6. In a carriage, the combination of a supporting frame, an annular way mounted on 95 said frame, a body, and a support on which said body is mounted comprising a pair of spaced members having downward offsets therein engaging within said way whereby the body is rotatably supported on the way. 100

7. In a carriage, the combination of a supporting frame, an annular way mounted on said frame, a body support comprising spaced members having offsets therein disposed within said way, the shoulder portions of said offsets having recesses therein receiving said way, and a latch on said body support coacting with said supporting frame. 105

8. In a carriage, the combination of a supporting frame, an annular way mounted on said frame, a body support comprising spaced members having offsets therein disposed within said way, the shoulder portions of said offsets having recesses therein 110 receiving said way. 115

In witness whereof, I have hereunto set my hand and seal in the presence of two witnesses.

CHARLES A. LINDBERG. [L. s.]
